UNITED STATES PATENT OFFICE

138,392

DESIGN FOR A SPIRIT LEVEL

William E. Bernard, Pittsfield, Mass.

Application May 2, 1944, Serial No. 113,441

Term of patent 7 years

(Cl. D52—1)

To all whom it may concern:

Be it known that I, William E. Bernard, a citizen of the United States, residing at Pittsfield, in the county of Berkshire and State of Massachusetts, have invented a new, original, and ornamental Design for a Spirit Level, of which the following is a specification, reference being had to the accompanying drawing, forming part thereof.

I claim:

The ornamental design for a spirit level, as shown.

WILLIAM E. BERNARD.
